(57) **CLAIM**

The ornamental design for a audio unit with MP3 player support, as shown and described.

DESCRIPTION

FIG. 1 is a top, front, left side, perspective view of an audio unit with MP3 player support showing my new design;

FIG. 2 is a top view thereof;

FIG. 3 is a front view thereof;

FIG. 4 is a rear view thereof;

FIG. 5 is a right side view thereof, the left side being a mirror image;

FIG. 6 is a bottom view thereof;

FIG. 7 is a perspective view thereof in an alternate condition;

FIG. 8 is a top view thereof;

FIG. 9 is a front view thereof;

FIG. 10 is a rear view thereof;

FIG. 11 is a right side view thereof, the left side being a mirror image; and,

FIG. 12 is a bottom view thereof.

The broken line showing of the drawing disclosure is for illustrative purposes only and forms no part of the claimed design.
